A. HOSMER.

Animal Stall.

No. 82,838.

Patented Oct. 6, 1868.

United States Patent Office.

ALFRED HOSMER, OF WATERTOWN, MASSACHUSETTS.

Letters Patent No. 82,838, dated October 6, 1868.

IMPROVEMENT IN STALLS FOR HORSES.

The Schedule referred to in these Letters Patent and making part of the same.

TO ALL WHOM IT MAY CONCERN:

Be it known that I, ALFRED HOSMER, of Watertown, in the county of Middlesex, and State of Massachusetts, have invented certain Improvements in the Construction of Stalls for Horses and other animals, and in the method of draining them, and floors where water is used for washing carriages, &c., of which the following is a full, clear, and exact description, reference being had to the accompanying drawings, making part of this specification, in which—

Figure 1 is a perspective view of a horse-stall having my improvements applied thereto.

Figure 2 is a transverse section through the same.

Figure 3 is a longitudinal section through the same, on the line xx of fig. 2.

Figure 4 is a perspective view of one of the gutters detached.

Figure 5 is a longitudinal section through the same.

Figure 6 is a perspective view of the under side of one of the strips or planks which form the floor of the stall.

The floors of animal-stalls, as now commonly constructed, are objectionable, for the reason that the drainage is very imperfect, rendering cleanliness impossible, while there is no means of preventing the saturation, (with urine,) and the consequent decay of the under floor and timbers beneath. Furthermore, in many instances the animal is compelled to stand upon an inclined surface, with an unbroken pitch in some one direction, from which result, first, constant discomfort, and secondly, the danger of producing permanent unsoundness of the limbs, as by becoming sprung.

My invention has for its object to overcome these difficulties, and consists in the employment of independent gutters, which receive and discharge the urine or other liquid, the construction of the gutters, and the manner in which they are applied, serving to entirely protect the under floor and the flooring-timbers from saturation, and the decay ensuing therefrom; thus avoiding the danger of the floor giving way and injuring the animal thereon, while, with a level floor, the drainage is immediate, rapid, and complete, perfect cleanliness is secured, and the straw used for bedding is kept dry, and lasts much longer than usual.

My invention also consists in an improved device for enclosing the space under the manger in which the straw or bedding is usually kept by day, and in admitting a current of air to the same, for the purpose of drying and purifying it.

To enable others skilled in the art to understand and use my invention, I will proceed to describe the manner in which I have carried it out.

In the said drawings, A A represent the sides of the stall, the floor of which is composed of longitudinal planks, b , laid on a level, and having a slight transverse curve or bevel on the upper surface, either in one direction, or in opposite directions from the centre, as may be deemed most desirable.

The planks b may be fastened down by the ordinary process of nailing, or may be secured in place by screws inserted from beneath, and are laid at a short distance apart, so as to leave spaces, c , between them, for the passage of the urine, which is received by gutters, B , directly beneath. These gutters are composed of metal or any other suitable material, and are so placed upon the flooring-timbers C as to present a level upper surface, which is flush with the lower flooring-boards d , upon which the planks b rest. The under surface of each of the planks b is slightly hollowed out or bevelled, as seen in fig. 2, so as to make a tight joint at the points 7 , and thus prevent the entrance of any liquid between the planks b and boards d , and their consequent saturation in the event of its overflowing the gutter; but in order to more effectually prevent the passage of the liquid between the floors, the planks b are each provided, on the under surface, with a groove, e , extending around both sides and across the rear end, as seen in fig. 6, the grooves lying over the spaces f , fig. 1, between the

boards *d* and the gutters *B*. These gutters are each provided with a groove, *g*, having two double inclines, each terminating at the centre in an opening or outlet, *h*, countersunk from beneath. At the forward extremity of the gutter the groove rises to its upper surface, but at the opposite end it descends slightly from the point *i*, and terminates in a semicircular outlet, *k*.

On the sides of the gutters *B*, over the points where they rest upon the timbers *C*, are projections, *l*, each of which is provided, on its upper surface, with a groove, *m*, fig. 4, which receives any liquid that may overflow the edges of the groove *g* at this point, and prevents it from coming into contact with the timber *C*, the base of each projection *l* lapping on to the inclined bottom of the gutter, down which the liquid will run, and be delivered at the lowest point, near the orifice *h*, through which the gutter is emptied. The lower boards *d* are laid close up to the projection *l*, spaces *f* being thus left between the boards and the gutters *B*, which spaces, in connection with the grooves *e* in the planks *b*, prevent the passage of any liquid between the two floors, as before stated. The short inclined portion of the groove *g*, at the rear end of the gutter, terminating in a semicircular outlet, *k*, is intended to drain the wide surface of the inclined plank *D*, running across the rear end of the stall-floor, the form of the under surface of the gutter at this point preventing any liquid from coming into contact with the flooring-timber adjacent thereto.

The inclined plank *D* forms a gutter, which will at once empty itself of any liquid, and can be easily cleaned of any solids, the incline being produced by dropping one of the timbers, *E*, a little below the level of those, *C*. The timber thus dropped is to be bolted, with intervening blocks, *o*, to each adjoining timber, opposite each stall-partition, and along under the partition is placed the usual bridging *G*, to render the floor firmer and more substantial. The blocks *o*, through which the bolt *S* passes, should be cut to conform to the bevel of the timber *E*, in case of extending the inclined plank *D* over and beyond it. The perpendicular edges of the bevelled planks *b* may be even with the sides of the grooves in the gutters *B*, or may project slightly inside of them, as seen in fig. 2.

As the whole length of the stall-floor obviously need not be provided with drainage, the portion *H*, upon which the fore-feet of the animal rest, consists of a close, level floor.

It is evident that a floor could be laid, having the gutters *B* applied thereto in a somewhat different manner to that above described; for instance, the upper bevelled planks *b* might be dispensed with, and the floor be of a single thickness only, in which case the gutters would be brought very nearly or quite up to the level of the upper surface of the floor, the grooves *g* themselves forming the draining-spaces. The flooring-planks, which might be bevelled or not, as preferred, would, in such case, be brought into close contact with the sides of the gutters *B*, so as to leave no spaces between, the lateral projections *l* being either dispensed with, or else let into the sides of the planks. Instead of planks, tiles with or without crowning-surfaces, laid in cement, could be placed between and in close contact with the gutters, if desired.

The gutters *B* may be constructed with any desired number of double inclines, from one upward, according to their length; or, instead of a double incline, the groove *g* may have a single incline only, extending from one extremity to the other, with one or more outlets; or a gutter having a straight, level groove may be employed, the desired incline being produced by pitching the gutter, without changing the level of the floor above.

I have spoken of my improved method of drainage as particularly applicable to the floors of stalls, as it effectually prevents the saturation with urine, and consequent decay of the under floor and timbers; but it is obvious that my improvements may be applied to other floors, without departing from the spirit of my invention, for instance, to that portion of a stable-floor upon which horses or carriages are washed, or, in fact, wherever it may be found useful and desirable.

A stall-floor constructed as above described, being level, and presenting no unbroken pitch in one direction, is more comfortable for animals to stand on, and prevents liability of injury to their limbs, while the drainage being immediate, rapid, and complete, the bedding-straw is economized, being kept dry, and consequently lasting longer, the portion which is unfit for further use being very small, while time is saved in grooming a horse that has lain upon a dry bed.

The space *I*, under the manger *K*, which is used for containing the bedding in the day-time, is closed by a slide or shutter, *L*, the upper edge of which is introduced into its proper place under the manger; then, by pushing the slide back against the upright cleats, *9*, it will drop into notches, *p*, one on each side, made between the lower portion of the casing and the cleats *9*, under the manger. In that position, having no handles or projections, it is beyond the possibility of removal by the animal within the stall, but it may be easily removed, for the purpose of gaining access to the space *I*, by raising it slightly, by means of the notches *q*, then pulling the lower edge forward and upward until it is horizontal, when it can be slid under the manger, out of the way, as seen in red in fig. 3. To facilitate this, the two ends of the slide are cut in the form of a curve, of which the radius is just equal to the greatest length of the slide.

By the employment of the slide or shutter above described, all hinges and fastenings, which are liable to get out of order, are dispensed with, and a ready and convenient means is afforded of opening or closing the space which contains the bedding, and by placing the bedding beyond the reach of the animal in the day-time, the floor can be kept cleaner, and there will be much less liability of the drainage-spaces in the upper floor being clogged, so as to obstruct the free escape of the liquid from the gutters beneath. Where there is a single stall only, an opening, *M*, for the admission of a current of air, should be provided on each side, communicating with the enclosed space *I* under the manger, but when there is a series of stalls, side by side, the space *I* should extend under all the mangers, without any partitions, a current of air being allowed to pass through from one end to the other, for the purpose of drying and ventilating the bedding contained therein.

I am aware that horse-stalls have been made with double floors, and with gutters, and I do not claim double floors as new, nor do I claim, broadly, inclined gutters, when applied to single or double floors.

What I claim as my invention, and desire to secure by Letters Patent, is—

The animal-stall A, when constructed and arranged substantially as and for the purpose described.

I also claim the gutter B, provided, by means of its position or form, with an inclined groove, having one or more outlets, and applied to a double or single floor, for the purpose of draining the same, substantially as described.

ALFRED HOSMER.
